(57) **CLAIM**

The ornamental design for a pet bed, as shown and described.

DESCRIPTION

FIG. 1 is a perspective view of the pet bed showing our new design;

FIG. 2 is another perspective view thereof with its pillow removed shown separately for ease of illustration;

FIG. 3 is a top plan view of FIG. 2;

FIG. 4 is a bottom plan view of FIG. 2;

FIG. 5 is a front view of FIG. 2;

FIG. 6 is a rear elevational view of FIG. 2;

FIG. 7 is a right side view of FIG. 2;

FIG. 8 is a left side view of FIG. 2;

FIG. 9 is a perspective view of the pillow, shown separately for ease of illustration;

FIG. 10 is a top plan view of FIG. 9;

FIG. 11 is a bottom plan view of FIG. 9;

FIG. 12 is a front elevational view of FIG. 9;

FIG. 13 is a rear elevational view of FIG. 9;

FIG. 14 is a right side elevational view of FIG. 9; and,

FIG. 15 is a left side elevational view of FIG. 9.
